SAFETY HEAD HOLDER FOR HEAD
SPLITTING MACHINES

Carl Oscar Schmidt, Jr., Cincinnati, Ohio, assignor to The Cincinnati Butchers' Supply Company, Cincinnati, Ohio, a corporation of Ohio

Application October 17, 1949, Serial No. 121,871

10 Claims. (Cl. 17—23)

1 This invention relates to a head holder and more particularly to a safety head holder for so-called animal head splitting machines of the type used in commercial butchering establishments.

An object of the invention is to provide a simple, foolproof, mechanical means for positively yet releasably holding irregular objects, such as animal heads, on a supporting surface.

Another object of the invention is to provide a safety head holder constructed and arranged for association with presently existing head splitting machines without necessitating structural changes therein.

A further object of the invention is to provide a safety holder which is manually operated by one hand of an operator, wherein the holding operation will be terminated incident to release of a control handle by an operator. In other words, the instant device cannot be used unless the operator pays attention to his job.

Still a further object of the invention is to provide a safety head splitting mechanism which includes means for controlling the electrical circuit to the electrically controlled actuating mechanism which drives the knife arm downwardly on its head splitting stroke. In the present invention the electrically controlled actuating mechanism is governed by means of a limit switch, in series with the motor control circuit, whereby the circuit will be closed only during those periods of time when the safety head holder mechanism has been manually actuated to assume a predetermined relationship.

Still another object of the invention is to provide safety means for a head splitting machine, which safety means contemplates the use of two switches in series with the motor control circuit, wherein the switches are located remote from the table top of the machine whereby accidental or unintentional energization of the motor control circuit cannot be effected in the absence of a deliberate act on the part of the operator to manipulate the two switches.

These and other objects are attained by the means described herein and as disclosed in the accompanying drawings in which:

Fig. 1 is a perspective view of a typical commercial animal head splitting machine provided with my safety features.

Fig. 2 is a front view of my safety head holding device associated with a head splitting machine, parts of which are indicated in broken outline.

Fig. 3 is a view of the right side of the device of Fig. 2.

2 Fig. 4 is an enlarged sectional view illustrating certain structural details comprising part of the present invention.

Figs. 5 and 6 are side views of modified forms of fingers comprising a detail of the present invention.

Fig. 7 is a diagrammatic representation of an exemplary control circuit for the motor drive of a commercial head splitting machine.

Fig. 8 is a side view of an exemplary driving mechanism for knife arm 12.

In commercial butchering operations animal heads are split apart in order to facilitate removal of the brain and portions of head meat which are utilized in the making of sausage. Such head splitting operations are usually accomplished by means of a mechanically actuated knife arm which is driven into an animal head supported upon the table top of the machine.

Heretofore it has been the common, but dangerous practice for the operators of such head splitting machines to hold the head to be split. On continuously operated splitters skill and dexterity are required to place or position the head accurately under the knife when it reaches its top position and hold it with both hands during splitting operation.

On intermittently operated splitters, the head is placed on the table top or head rest with both hands. The head is then held with one hand while utilizing the other hand to manipulate the controls for causing the machine to operate.

The intermittently operated splitter is an improvement over the continuously operated type and the safety head holder of the present invention is to be used only with the intermittently operated splitter, which is equipped with an electric limit switch to stop splitter after each splitting cycle.

When heads are held by hand the operator is not only subjected to unnecessary dangers but the head splitting action is quite often unsatisfactory by reason of the fact that the head is not firmly positioned incident to the splitting action of the power driven knife arm.

With reference now to Fig. 1, the numeral 10 denotes generally a commercial head splitting machine which includes a knife arm 12, the free outer end of which is provided with suitable

50 head splitting knives 14. It should be noted that the mechanism illustrated is a hog-head splitter; however, the present invention is applicable to all mechanical head splitting mechanisms, whether hog, sheep, calves, beef, or otherwise.

55 Knife arm 12 may be pivoted as at 16 for

movement between raised inoperative position and lowered operative position, by means of a suitable drive mechanism which, by way of example, may include a yoke 18, an electric motor 20 and suitable means, such as, by way of example, disclosed in Fig. 8, for translating the rotary motion of the motor to an oscillatory motion of the yoke. Motor 20 may be coupled to a suitable speed reduction device 15 which includes a driven gear 17 enmeshed with gear 21 secured to and carried by shaft 23 rotatably journaled to and between a pair of laterally spaced brackets 25. The opposite ends of shaft 23 may be provided with crank arms 27 to which the lower ends of the yoke arms 18 may be pivotally secured as at 15 19. Motor 20 and brackets 25 may be suitably secured to and suspended from table 13. At this point it should be clearly understood that the present invention is neither concerned with nor directed to the particular structural details of the head splitting mechanism, but is rather concerned with the safety features hereinafter more fully described.

The heads to be split are placed upon table top 22 and after being centered and steadied are ready to be subjected to the splitting action of knives 14. Heretofore operators have steadied the heads with one hand, using their other hand to manipulate suitable knife-arm-actuating controls. The primary object of the present invention is to provide a mechanical head holder which will eliminate the present hazards by making it necessary for an operator to place his hands at certain definite locations or stations to render the machine operative.

With particular reference now to Figs. 2 and 3, it will be noted that my improved safety head holding device includes two laterally spaced rows of head engaging fingers 30, which are illustrated in their fully raised, inoperative, non-clamping positions.

As best disclosed in Fig. 3, each finger 30 may include a boss portion 32 dimensioned to engage shaft 34 suitably journaled as at 36 in bearing brackets 38. Preferably, though not necessarily, brackets 38 may be one-piece, as illustrated, and include upstanding end portions 39 and a lower portion 40 constructed and arranged to be secured to the framework of an existing head splitting machine by means of bolts 42, or the like.

The axis of each shaft 34 is disposed along an edge of table top 22.

If desired, fingers 30 may be secured directly to shafts 34, however, in the preferred embodiment of the invention each of fingers 30 are connected in yieldable driven relationship with their respective shafts, thereby enabling the fingers to conform to the irregular contour of an animal head or other irregular object supported on table top 22.

To provide the desired yieldable driven relationship between fingers 30 and shafts 34, collars 44 may be provided, one for each finger, wherein each collar is dimensioned for a slip fit with shaft 34. Suitable fastening means, such as a set screw 46 (Fig. 4) may be provided for enabling the various collars to be fixedly secured to shaft 34 in any desired relationship therewith. Resilient driving members, such as coil springs 48 may be provided around shafts 34, one between each finger and its associated collar and with their opposite ends fastened to a collar and its associated finger, respectively.

With the reference again to Fig. 3, it will be noted that any turning motion imparted to shaft 75

34 will be imparted directly to collars 44 which are fixedly secured thereto; and that such turning motion will be imparted to fingers 30 through the various resilient connector elements, or springs 48. This construction facilitates relative movement between each finger and its shaft as well as between the individual fingers mounted on the shaft, thereby making it possible to positively engage an irregular article, such as an animal head, for holding it tightly against or on table top 22 utilizing only two rows of fingers.

A crank arm 60 may be secured to one end of each of shafts 34 and in overhanging relationship with the forward end of the machine, as best illustrated in Figs. 1 and 3. The free outer end of each crank arm is pivotally connected, as at 62, to levers 64, the other ends of which are pivotally secured as at 66 to a common axis, as by a stud 68.

Guide means, denoted generally by the numeral 70, may be fastened to the forward end of the head splitting machine by bolts 72, or the like. The guide means includes a base plate 74 on which a follower member 76 is slidably mounted. Suitable means may be provided for guiding and insuring the desired sliding relationship between follower 76 and member 74, such as, by way of example, L-shaped laterally spaced strips 78, which are secured to and carried by member 74 with adjacent portions disposed in overlapping relationship with the side edges of the follower. Stud 68 is secured to and carried by the follower, and for convenience, a hand grip member 80 may be provided as best illustrated in Fig. 3.

The axis of travel of follower 76 should be at substantial right angles with table top 22, or, stated another way, at right angles with a line drawn through the centers of shafts 34.

From the foregoing, it will be apparent that a lifting force applied to hand grip 80 will result in elevation of the follower and the concurrent turning of each of shafts 34 inwardly toward one another for lowering their respective fingers over the table top.

The effectiveness of fingers 30 for positioning and holding an article upon table top 22 is contingent upon and a function of the lifting force applied through handle 80, it being understood that the greater the lifting force the more positive an article will be engaged by the fingers. Release of handle 80 will result in lowering of follower 76 and the automatic release of the article on the table top incident to return of fingers 30 to their upstanding, inoperative positions illustrated in Figs. 1, 2 and 3.

In the preferred embodiment of the invention I not only provide the hereinabove described means for securely though releasably holding an irregular object onto table top 22, but go further and provide means for rendering the head splitting mechanism inoperative during those periods of time when the head holding mechanism is inoperative. This is accomplished by providing a limit switch 90 in series with the control circuit of motor 20. As clearly illustrated in Fig. 3, limit switch 90 may include an arm 92, movable between raised or elevated circuit-making and lowered circuit-breaking positions. The free outer end of arm 92 may be provided with a rotatable member 94 adapted to ride upon the rear face of follower 76, which may be provided with a stepped portion or offset 77 defining rear faces 79 and 81. In Fig. 3, it will be noted that follower 76 is in a fully lowered circuit-breaking position. As handle 80 is elevated for mov-

ing fingers 30 downwardly into article engaging position, arm 92 of the limit switch will be elevated to a circuit-making position incident to transition from face 79 to 81, thereby energizing motor 20 of the device for driving knife arm 12 downwardly in a head splitting cycle. If the operator should accidentally or deliberately permit handle 80 to be lowered, during the head splitting cycle, the electrical circuit to motor 20 will be interrupted incident to movement of member 94 from face 81 to 79, thereby instantly stopping the downward power stroke of knife arm 12. It is apparent, therefore, that the mechanism can be operated only in response to an intentional, deliberate act on the part of an operator.

In order to further enhance the safety characteristics of the head splitting machine, a second switch, denoted generally by the numeral 100, may be placed in series in the motor control circuit; and to insure that both hands of an operator are in a safe place while the knife arm is being lowered on a power stroke, switch 100 is located remote from handle 80, such as, by way of example, along the upper side edge of the framework, thereby making it necessary for an operator to deliberately and concurrently use one hand to lift handle 80 and his other hand to actuate switch 100 in order to render the machine operative.

In order to increase the frictional engagement between a finger and the object held thereby, the finger denoted generally by the numeral 130 and having at least one serrated edge 132 (Fig. 5), may be utilized in lieu of fingers 30.

In Fig. 6 a modified type of finger is illustrated which comprises a collar portion 140 and a resilient finger portion 142 which may be fabricated from suitable material characterized by its inherent flexibility. If desired, the strip of resilient material may be replaced with a coiled, spring-like member.

In those instances where resilient fingers are utilized, collars 140 may be fixedly secured directly to shafts 34, in which event collars 40 and the resilient connected elements 48 may be omitted.

With reference again to Fig. 3, it will be observed that one side of each finger boss 32 may be undercut as at 50 for providing an abutment 52, and that each of collars 44 which are immediately adjacent a finger boss may be provided with an interfering member 54 constructed and arranged to engage abutments 52 incident to relative motion between a finger and its associated collar beyond a predetermined amount as defined by the spacing between adjacent faces of each abutment and its associated interfering member.

In this manner I have provided means for enabling an operator to actuate shafts 34 until at least one of fingers 30 is forced against an object positioned on table top 22 by reason of a direct driving relationship of that finger through its associated collar 44. The other fingers will be urged in contact with other portions of the object by means of their respective resilient connector element 48.

It will be observed that collar 44 adjacent the left end of bracket 38 has not been provided with an interfering portion 54 because of its bearing relationship with the bracket.

From the foregoing, it will be noted that I have not only provided positive means for holding a head incident to a splitting operation, but have

likewise provided simple, yet highly effective, means for precluding accidental or unintentional operation of the splitting mechanism whereby an operator cannot be injured incident to normal and intended operation of the machine.

What is claimed is:

1. For use in a head splitting machine comprising means for splitting the head, a holder including an elongated table-like support for the head, the head support including side and end edges, a rotatable shaft carried by the support adjacent each side edge in spaced parallel relationship, a plurality of spaced yieldable fingers mounted on each shaft and directly connected thereto in yieldable driven relationship, the fingers normally extending substantially vertical from the outer circumference of the shaft and between the ends thereof, the table being adapted to support a head thereon between the shaft and fingers, means operatively associated with the shafts for rotating the shafts to cause the fingers to move toward each other and thereby engage the head at different spaced points and horizontal planes to hold and position the head on the table support, and the engagement of the fingers with the head being such that the upper portion of the head is exposed so that while so held and positioned it can be split.

2. The structure as defined in claim 1 wherein the fingers are connected to the shafts by a resilient member for each finger with the opposite ends of the resilient member being secured relative to a finger and the associated shaft.

3. The structure as defined in claim 1 wherein the fingers are connected to the shafts by an actuating element for each finger secured to and driven by the shaft and yieldable means interconnecting each finger in driving relationship with its associated actuating element.

4. The structure as defined in claim 1 wherein there is means actuated by the shaft rotating means to cause completion of a circuit to a driving means for the head splitting means.

5. The structure as defined in claim 1 wherein the shaft rotating means comprises crank arms operatively associated with each shaft, levers pivotally secured to each crank arm, a guide means, a follower slidable in the guide means, each of the levers being pivotally interconnected with the follower, and means for operating the follower.

6. The structure as defined in claim 5 wherein there is an electrical switch actuated by the follower when moved in a guide means to close a circuit to a driving means for the head splitting means.

7. The structure as defined in claim 6 wherein there is a manually operable normally open switch in series with the driving means and the first mentioned switch mounted on the machine at a point removed from the first mentioned switch.

8. For use in a head splitting machine comprising means for splitting a head, a holder including an elongated table-like support for the head, the head support including side and end edges, U-shaped brackets mounted on the support adjacent each side edge, rotatable shafts journaled in each of the brackets and positioned slightly above the support in spaced parallel relationship, a plurality of spaced fingers mounted on each shaft, the fingers normally extending substantially vertical from the outer circumference of the shaft and between the ends thereof, an actuating element for each finger secured

to and driven by the shaft, yielding means mounted on the shaft between the actuating element and its associated fingers in driving relationship with the actuating element and its associated finger, the table being adapted to support a head thereon between the shafts and fingers, crank arms operatively associated with each shaft, levers pivotally secured to each crank arm, a slide member mounted below the support and disposed on an axis at substantial right angles with the mean plane of said support, a follower carried by the slide and movable therein, each of the levers being pivotally connected with the follower and means for operating the follower to rotate the shafts to cause the fingers to move toward each other and thereby engage the head at different spaced points and horizontal planes to hold and position the head on the table support, and the engagement of the fingers with the head being such that the upper portion of the head is exposed so that while so held and positioned it can be split.

9. The structure as defined in claim 8 wherein there is a driving means for the head splitting means, an electrical circuit for the driving means, and an electrical switch in the circuit actuated by the follower when moved in the slide to close the circuit to the driving means for the head splitting means.

10. In a head splitting machine having means for holding and splitting heads, said holding means including a supporting table, a pair of laterally spaced U-shaped brackets, means for securing said brackets relative to the supporting table, a shaft journaled in each bracket, a plurality of fingers carried by and rotatably mounted on each shaft, an actuating element for each

15 finger secured to and carried by the shafts, and means yieldably interconnecting each finger in driving relationship with its associated actuating element, a crank arm secured to each of said shafts, a pair of levers, one end of each of said levers pivotally secured to each crank arm, means pivotally connecting the other ends of said levers and operating means connecting to said last named means for synchronizing the action of said shafts incident to movement of said last mentioned means.
